CLAIM

The ornamental design for an eductor inlet, as shown and described.

DESCRIPTION

FIG. 1 is a front-top-right perspective view of an eductor inlet according to the claimed design.

FIG. 2 is a top view of the eductor inlet.

FIG. 3 is a bottom view of the eductor inlet.

FIG. 4 is a rear view of the eductor inlet.

FIG. 5 is a front view of the eductor inlet.

FIG. 6 is a right side view of the eductor inlet; and,

FIG. 7 is a left side view of the eductor inlet.

The broken lines shown in the figures are for the purpose of illustrating portions of the eductor inlet that form no part of the claimed design.

1 Claim, 5 Drawing Sheets
